Sacks, P.C.(57) **CLAIM**

The ornamental design for a latch, as shown and described.

DESCRIPTION

FIG. 1 is a top, front, and right side perspective view of a latch showing my new design;

FIG. 2 is a left side elevation view thereof;

FIG. 3 is a right side elevation view thereof;

FIG. 4 is a top plan view thereof;

FIG. 5 is a bottom plan view thereof;

FIG. 6 is a front elevation view thereof; and,

FIG. 7 is a rear elevation view thereof.

The long dash-short dash broken lines in the figures represent boundaries of the claimed design and form no part thereof. All other broken lines represent portions of the latch that form no part of the claimed design.
